SOFA

Henry P. Glass, Chicago, Ill.

Application July 22, 1957, Serial No. 47,030

Term of patent 7 years

(Cl. D15—11)

The end of the sofa not visible on the drawing is similar to the end shown.

The characteristic features of my design reside in front portions of the sofa, the rear thereof being conventional.

I claim:

The ornamental design for a sofa, substantially as shown and described.
